SELECTIVE ELECTRIC SIGNALING SYSTEM

Edward S. Ruth, Norwalk, Conn., assignor to Edwards and Company, Inc., Norwalk, Conn., a corporation of New York

Application February 4, 1948, Serial No. 6,297

5 Claims. (Cl. 177—353)

1

This invention relates to selective electric signaling system.

An object of the invention is to improve selective signaling systems such as signaling circuits for use in apartment houses, dormitories, schools and the like and for other applications where selective signaling is required.

Another object is to provide a selective signaling system requiring a reduced number of signaling conductors.

A further object is to provide a signaling system for signaling any one of several stations selectively over conductors which are common to two or more of the stations.

A still further object is to provide a selective signaling system for calling any one of a plurality of stations from a master station and for signaling the master station from the individual stations.

A specific object of the invention is to provide a return call system for selective calling stations located in various rooms in a building or group of buildings from a central switchboard or master station.

A further object is to provide a signaling system for calling a plurality of individual stations selectively from a master station and for notifying the master station of the receipt of the signal by the individual stations.

Other objects are to provide suitable circuits and apparatus for carrying out the aforementioned objects.

Other objects of the invention will be apparent from the following description and accompanying drawings taken in connection with the appended claims.

The invention accordingly consists in the features of construction, combination of elements, and arrangement of parts as will be exemplified in the structures to be hereinafter described and the scope of the application of which will be indicated in the following claims.

In the accompanying drawings in which are shown by way of illustration several possible embodiments of my invention:

Figure 1 is a circuit diagram of a return call selective signaling system embodying features of the invention and comprising a master station or switchboard and a plurality of individual stations to be called, together with signaling means for indicating at the master station that an individual station has been called and for further indicating at the master station the receipt of a signal by an individual at the called station;

Figure 2 is a circuit diagram of a modified

2

master station circuit embodying the use of a telephone type of calling dial for signaling individual stations;

Figure 3 is a circuit diagram showing a further modified master station circuit having a common return signal device; and

Figure 4 illustrates a further modified master station circuit.

In apartment houses, dormitories, schools and a number of other locations there is frequently a need for signaling systems whereby any one of a number of rooms or stations can be called from a central location or master station. Thus, in dormitories an office or attendant's desk is frequently located near the entrance to the building or, in the case of a group of buildings, in one of the buildings of the group. When a visitor calls at the attendant's desk for one of the occupants of the dormitory or when a telephone call is received on the house telephone it is usually necessary to provide some form of electric calling system whereby the attendant can signal the room of one of the occupants and receive a signal back from the occupant indicating that the calling signal has been received. Buzzer systems have been provided in the past requiring a pair of conductors leading to each call station or at least one conductor individual to each station.

In apartment houses where no attendant is provided a push button panel is frequently located at the entrance to the building to enable a caller to call any individual apartment and push buttons are provided in the apartment for answering the call or for unlatching the entrance door to the building. These likewise require at least one conductor to each apartment station.

The present invention contemplates a circuit in which several stations are served by common conductors, the arrangement being such that individual conductors are not required for each station and means are provided whereby any station may be called or may signal the master station without effecting the signaling devices associated with other stations.

The invention makes possible a great reduction in the size of the master station switchboard required with resultant greater operating efficiency, reduced space requirement and greater portability and convenience of use of the master station.

According to the preferred method of practicing the invention rectifier means are associated with the individual stations so that certain of the signaling apparatus at the main station, or both, prevent the fortuitous operation of signal-

ing devices associated with uncalled stations or any inactive parts of the master station during the calling of an individual station or the calling of the master station from an individual station.

While a preferred embodiment of the invention is described herein, it is contemplated that considerable variation may be made in the method or procedure and the construction of parts without departing from the spirit of the invention. In the following description and in the claims, parts will be identified by specific names for convenience, but they are intended to be as generic in their application to similar parts as the art will permit.

Referring to the drawings, Figure 1 shows a selective electric signaling system suitable for calling the individual rooms of a dormitory or apartments of an apartment house or an apartment house group from a central point such as an operator-attendant switchboard or a signaling panel. The portions of the circuit on the left hand part of the drawing to the left of the dot and dash line represent those parts which are located at the master station or switchboard and the circuits on the right hand part of the drawing represent the individual room or apartment station circuits. The conductors shown crossing the dot and dash line are the ones extending from the master station to the various groups of individual stations. It will be noted that these are relatively few in number and since they may be of considerable length where the separation of the master station from the call stations is great, the present circuit arrangement represents a considerable saving in wiring arrangements over prior art arrangements requiring one or more conductors connecting each individual station with the master station.

Assuming that the circuit is installed in a dormitory the groups of stations shown on the right hand part of the drawing may represent the stations located in the individual dormitory rooms. For purposes of illustration it will be assumed that the lowermost four stations shown in the drawing, indicated by reference numerals 101, 201, 301 and 401, are the stations located in the first room on the first, second, third and fourth dormitory floors respectively. The next four stations indicated by numerals 102, 202, 302 and 402 will then represent the stations located respectively in the second room on each floor and so on to the uppermost stations shown, which will represent the signaling station located in room 404; in other words, the fourth room on the fourth floor of the building. While not necessarily so, all of the room stations will generally be similarly equipped. Station 404, as illustrated, comprises a buzzer 10, an answering key 11 and, according to the present invention, a half-wave rectifier 12 such as a plate rectifier of the copper oxide or selenium type. The back contact 13, answering key 11, buzzer 10 and rectifier 12 are all connected in series between terminals 14 and 15, which represent the terminal connections to the two signal conductors entering the room. An answering conductor 16 is also provided connecting the front contact 17 of answering key 11 at the station.

At some or all of the stations it may be desirable also to provide visual indicators such as a drop annunciator in addition to the buzzer. This station 304 is provided, as shown, with a drop annunciator 18 whose winding is connected in series with buzzer 10. When the room is called the buzzer will operate to give an audible signal,

at the same time drop 18 will fall to give visual indication that the room has been called. When the occupant answers drop 18 can be manually reset.

The master station comprises a switchboard provided with a series of telephone jacks comprising sleeve contacts such as 21, 22, 23 and 24 and tip contacts 31, 32, 33 and 34. The switchboard is also provided with a series of push buttons such as push buttons 1, 2, 3 and 4.

Switchboard lamps 41, 42, 43 and 44 are associated respectively with the telephone jacks. An individual lamp control relay is associated with each jack and is provided with relay contacts 81, 82, 83 and 84 respectively for closing the lamp energizing circuits 91, 92, 93 and 94 respectively in response to the energization of operating windings 51, 52, 53 and 54 respectively of the relays. A lamp energizing transformer 25 has its secondary winding connected at one end to common conductor 26 leading to all of the lamps and at the other end to common conductor 27 leading to one of the contacts of each of contact pairs 81 to 84, the other contact of each pair being connected respectively to the individual lamp energizing circuits 91 to 94 respectively. Relay reset windings 61, 62, 63 and 64 respectively are associated with respective lamp control relays for opening the lamp circuits after they have been closed by the operating reset windings. Each of the reset windings has connected in series with it a half-way rectifier, namely rectifier 71 to 74 respectively. Each of the reset windings are connected between common conductor 26 and signaling conductors 111, 112, 113 and 114 respectively leading respectively to the individual room station groups having the same last digit. For example, signaling conductor 114 leads to terminal 14 and hence to keys 11 and individual room stations 104 to 404 inclusive.

A second power supply transformer 28 for supplying signaling current has its secondary winding connected between one terminal of each of push buttons 1, 2, 3 and 4 and the sleeve contact 29 of the switchboard plug. The tip contact 30 of the plug is connected by conductor 35 through normally-open push button switch 36 to common conductor 27. Push button 36 is located at the master station for the purpose of resetting the signal lamp relays in case a called station does not answer.

Push buttons 1 to 4 respectively are connected to signaling conductors 1a, 2a, 3a and 4a respectively which lead to all of the room stations on a respective floor.

The operation of the system can be carried out as follows:

When the operator at the master station wishes to call an individual room station, say room 404, she inserts the switchboard plug in to the jack associated with all of the rooms ending in the digit 4, namely jack 24 in the present example. She then pushes the push buttons associated with the floor desired. In the present instance, push button 4.

When room 404 is thus called the signaling circuit is complete for operating room buzzer 10 at station 404 as follows:

From the secondary winding of transformer 28 through push button 4, conductor 4a, terminal 15, rectifier 12, buzzer 10, the normally-closed back contact 13 of key 11, key 11 and the individual room station conductor to terminal 14, conductor 114, relay winding 54, sleeve 24 of the switchboard jack, sleeve contact 29 of the switchboard

plug and conductor 37 to the opposite terminal of the secondary winding of transformer 28. Signaling current through this circuit operates buzzer 10 to give an audible signal at individual room station 404 and energizes relay winding 54 to close relay contacts 84 to light signal lamp 44. The lamp energizing circuit extends from the secondary winding of transformer 25 to conductor 26, lamp 44, conductor 94, relay contacts 84, and common conductor 27 back to transformer 25. This gives a visual signal or indication at the switchboard that the room has been called.

When the occupant of the room hears the buzzer he is supposed to answer by pressing key 11 momentarily. As key 11 is pressed a reset circuit is closed to extinguish signal lamp 44 as follows:

From the right hand end of transformer 25 through common conductor 16, front contact 17 of key 11, key 11, the individual room circuit to terminal 14, conductor 114, rectifier 74, relay reset winding 64, common conductor 26 back to the left hand end of the secondary winding of transformer 25. This energizes winding 64 to open relay contacts 84 and thereby extinguish the lamp.

Should the room occupant fail to answer the operator at the master station can extinguish the lamp simply by pressing push button 36 which closes an operating circuit for reset winding 64 from transformer 25 through conductor 35, plug tip 30, jack contact 34, rectifier 74, winding 64 and common conductor 26 back to the transformer.

The advantages and function of the rectifiers variously located in the circuit will now be apparent. First as to rectifiers 12 located at each individual room station; if room station 404 is being called current is supplied from the secondary winding of transformer 28 through push button 4 and conductor 4a to the room station. However, conductor 4a is also connected to all other stations on the fourth floor, such as stations 401, 402, and 403 and hence one side of each of these room station circuits is bridged together. Similarly for stations on each of the other floors. However, certain groups of stations are also bridged together in another way as by conductors 111, 112, 113 and 114 respectively, each of which is connected to a group of stations ending in the same digit. Without the rectifiers 12 in the circuit it would thus be possible for signaling current passing through push button 4 and conductor 4a to find its way back to the transformer, not only through station 404 which is intended to be called but also through several other paths such as follows:

From conductor 4a through station 403 and via the portion of conductor 113 which connects the stations ending in digit 3 together, then through stations 103, 203 and 303 to conductors 1a, 2a and 3a respectively. From these conductors the current can find a ready return path to transformer 28 through stations 104, 204 and 304 respectively, conductor 114, relay winding 54, sleeve contact 24, plug sleeve 29, the plug being at this time inserted in sleeve 24, and conductor 37 back to transformer 28. However, with rectifiers 12 in each station circuit, each rectifier being directed to pass current through its station in the same direction, such a return path is blocked. Thus, while current could find its way via conductor 4a through station 403 to conductor 113 it would be blocked from finding a return path to the transformer since, at this time, the switchboard plug is not connected to sleeve 23 and the rectifiers 12 at individual stations 103, 203 and 303 are biased

in the direction which prevent current flow from conductor 113 through the stations to conductors 1a, 2a and 3a.

It will thus be evident, that by use of rectifiers 12 at the individual stations, a large number of room stations can be called from the central switchboard or master station, over a small number of conductors. In the example illustrated only four floors and four stations per floor are indicated. However, it will be apparent that both the number of floors and the number of stations per floor can be increased or reduced. In general, one additional conductor leading from the master station is required for each additional floor being served by the switchboard and one additional conductor is required to be added for each additional group of room stations ending in the same digit. The advantages thus become more evident when a large building or a large number of stations are served.

The function of rectifiers 71, 72, 73 and 74, located at the master station, is to prevent another condition in which room stations might be fortuitously called. For example, in the absence of rectifier 74 when station 404 is called the signaling current would also find a path for calling station 403 from push button 4 through conductor 4a, station 403, conductor 113, rectifier 73, winding 63, winding 64, conductor 114, winding 54, sleeve 24, plug sleeve contact 29, and conductor 37 back through transformer 28 to the push button. The rectifiers 71 to 74 prevent such "sneak" circuits which would interfere with the proper functioning of the system.

Figure 2 is a circuit diagram of a modified signaling system in which the stations are called by use of a telephone type dial in combination with a series of push buttons. The figure shows only the master station since the individual room station circuits are similar to those illustrated in Figure 1. Circuit conductors and circuit elements have been given the same reference numerals where they are similar in function and relative location in the circuit.

In addition to current supply transformers 25 and 28 a third transformer 212 is provided which supplies dialing current from full-wave rectifier 213 to dial 214 and winding 218 of stepping switch 217. Output conductor 219 connects one contact of the dial to the rectifier and conductor 220 connects the other output terminal of the rectifier to winding 218 of the stepping switch. The dial pilot lamp 215 is connected between conductor 219 and conductor 227 leading to pilot light contact arm 224 on the stepping switch.

A reset key 216 is also connected between conductor 219 and interrupter contact spring 225 of the stepping switch. Conductor 228 connects dial 214 to stepping winding 218.

If desired, for convenience, dial 214, pilot light 215, reset key 216, floor push buttons 1, 2, 3 and 4, switchboard lamps 41, 42, 43 and 44, resetting push button 36 and a buzzer 211 may all be installed at the operator's location as indicated by the dashed rectangular 229, while stepping switch 217 the relays having windings 51 to 54, current supply transformers 25, 28 and 212, and rectifier 213 may be located in another space such as in a closet or in the basement of the building.

In operation of the dial system shown in Figure 2, assuming the operator wishes to call station 404 (Figure 1) from the master station shown in Figure 2, the operator will simply dial

the station digit on dial 214, namely the numeral 4. Operation of the dial effects closure of the dial contacts momentarily four times in sequence. Each time the dial contacts are closed an energization circuit for stepping relay winding 218 is closed as follows:

From rectifier 213 via conductor 219, dial 214, conductor 228, winding 218 and conductor 220 back to the rectifier. Energization of the winding 218 causes it to step contact arms 221, 222, 223 and 224 ahead one position for each energization of the winding, the arms engaging co-operating contacts arranged in an arc around them as they are advanced each step. Thus, arm 221 will be advanced to the fifth contact to close a circuit from transformer 28 via conductor 37, contact arm 221, conductor 234, relay winding 54, conductor 114 to all room stations ending in the digit 4. When push button 4 is pressed, after this circuit has been established, the circuit is completed through room station 404, conductor 4a, push button 4, master station buzzer 211 and conductor 210 back to transformer 28, thereby operating the buzzer at room station 404 and simultaneously operating the buzzer at the master station to indicate to the operator that the station is being called. Relay winding 54 is also energized and operates its armature to close contacts 84, thus completing the circuit for signal lamp 44 giving a visual indication to the operator that a station ending in the digit 4 is being called.

When the person at station 404 answers by operating answering key 11 a circuit is completed for extinguishing lamp 44 as follows:

From the secondary winding of transformer 25 via conductor 16 through room station 404, then via conductor 114, rectifier 14, winding 64 and conductor 26 back to transformer 25.

Winding 64 thereupon opens contact 84 to extinguish the lamp.

Should no answer be received from the called station the operator can extinguish lamp 44 by momentarily pressing push button 36 which closes a circuit from transformer 25 via conductor 16, push button 36, conductor 235, selector switch arm 222, conductor 236, rectifier 14, winding 64 and conductor 26 back to the transformer. Contact arm 222, in the second bank of the selector switch, serves the purpose of connecting push button 36 to the reset winding of any digit push button 36 to the reset winding of any digit dialed by the operator so that the indicating lamps may be selectively extinguished before calling a second station. But, it also is possible for the operator to call a second station while she is awaiting a response from the first station by later redialling the first station for the purpose of extinguishing the first station signal by push button 36 if a response is not received from that station.

In order to restore selector switch 217 to its normal or "home" position reset key 216 is provided. Thus, when the selector switch arms are on any selected station position the switch may be returned to normal by momentarily pressing push button 216. This closes a stepping circuit through interrupter contacts 225 of the stepping switch and switch arm 223 through operating winding 218. Contacts 225 are opened by the switch mechanism at each station position of the switch arms, thus allowing the stepping lever controlled by winding 218 to fall back. However, in doing so the lever closes contacts 225 to reenergize winding 218 and to advance the switch another position. Hence, while reset key 216 is

closed the switch will automatically step around until it is returned to "home" position in which all contact arm circuits are opened and the winding 218 is de-energized.

Contact arms 221, 222 and 224 are "non-bridging" with respect to their associated contacts. That is, the circuit through the contact arms is momentarily opened while the arms are being transferred from one contact to the next succeeding contact of the bank. Contact arm 223, however, is preferably of the bridging type so that the circuit is entirely under control of interrupter contacts 225 as long as reset key 216 is closed and the switch is not at "home" position.

Contact arm 224 closes the circuit at each digit position for pilot lamp 215 so that when a digit is dialed a pilot lamp flashes momentarily as the switch advances each position. This indicates to the operator that the selector switch is operating properly in response to the dial.

It is obvious that where the number of room stations on a floor exceed the number of digits on the calling dial the selector switch can be in two or more stages. The operator will then dial one number to select the "tens" digit thereby setting up a first rotary switch to a contact leading to a second rotary switch. The operator then dials the "units" digit to set up the selected position on the second switch. The two switches together then will complete the circuit to the room station selected when the desired floor key is pressed.

Figure 3 illustrates a further, and more simplified master station circuit for calling individual room stations similar to those shown in Figure 1. Such a circuit is useful, for example, at an unattended location such as the entrance to an apartment building where an operator is not provided. The master station comprises a switchboard having a series of jacks such as jacks 321, 322, 323 and 324 connected to conductor 111, 112, 113 and 114 respectively leading to the room stations. Push buttons corresponding to each floor are also provided such as push buttons 1, 2, 3 and 4 for closing circuits over conductors 1a, to 4a respectively. The switchboard plug comprises a single sleeve contact 329 for engaging the sleeves of jacks 321 and the like.

An answering buzzer 311 is also provided which is connected through rectifiers 331, 332, 333 and 334 respectively to conductors 111, 112, 113 and 114 respectively. Transformers 25 and 28 provide power supply for signaling current.

When a person wishes to call a room station he places the switchboard plug in the jack whose identification number ends in the digit of the call station desired and pushes the button corresponding to the floor on which the station is located. Thus, if station 404 is desired the plug is placed in jack 324 and push button 4 is pressed. This closes a signaling circuit from transformer 28 via conductor 37, plug contact 329, jack 324, conductor 114, room station 404, conductor 4a, push button 4 and conductor 310 to transformer 28. In this system the room station is called but no indication is given by the switchboard during calling. However, when the person at the room station answers, a circuit is completed for operating answering buzzer 311 from transformer 25 via conductor 16, room station 404, conductor 114, rectifier 334, buzzer 311 and conductor 26 back to transformer 25.

Rectifier 331 et al. prevent signaling current from transformer 28, during the calling of an in-

dividual station, from passing over conductors leading to other groups of stations which might otherwise be fortuitously called. In the absence of these rectifiers when station 404 is being called a circuit would also be closed for calling station 403 from jack 324 over conductor 312 to jack 323 and over conductor 113 to the room station. Similar circuits would also be closed for calling all other stations on the fourth floor. However, rectifiers 331 to 334 are so biased that current 10 sent over one conductor cannot find its way to any of the others.

Figure 4 is a circuit diagram of a further modified system. This system is generally similar to the system illustrated in Figure 1 and the operation is substantially the same. However, in this system the rectifiers 12 are not located at the individual room stations but are grouped together in a power unit which may be located at any convenient location in the building where the individual room stations are located, such as in the basement or a service room. The power unit indicated by a reference numeral 410 may include, in addition to the banks of rectifiers 12, the transformer unit comprising transformers 25 and 28.

The master station, indicated by reference numeral 411 may be located at a point remote from the power unit and from the room stations, such as in another building. The number of conductors connecting the master station with the power unit are relatively small, by virtue of the use of the rectifiers arranged according to the present invention.

A single room station 404 is illustrated in Figure 4, the other room stations being similar and the connecting circuits being readily apparent from the diagram. Referring to room station 404 it will be noted that it is similar to the room station previously described in connection with Figure 1 with the exception that rectifier 12 is not located at the station position. The signalling circuit extending from push button 4 over conductor 4a has connected to it conductor 404a leading from the room station and similar conductors leading from all other room stations on the fourth floor. Conductor 404b extending from answering key 11 at the room station, is individual to station 404 and extends to one of the rectifiers 12, located in the power unit 410 and hence over conductor 114 which is common to all stations ending in the digit 4 to the master station. Answering conductor 404c extending from answering contact 17 of key 11 is connected to a conductor 16a which is common to all stations on the fourth floor. Conductor 16a, in common with similar conductors 16b, 16c and the like leading from the other floors are all connected to the return conductor 16 in the power unit.

The system of Figure 4 has the advantage of simplified room stations and the location of the rectifiers and transformers in a service room where they can be readily checked and serviced at any time without disturbing the room occupants. This is of particular value in hospitals and similar institutions.

Since the operation of the system of Figure 4 is similar to that of Figure 1, it is not believed necessary to describe it in further detail.

It will be seen that a selective electric signaling system has been provided in accordance with the present invention in which the number of conductors required have been greatly reduced without limiting the functioning of the system.

One of the greatest advantages of the system

5 resides in the greatly reduced switchboard area required. In the past such switchboards have often required so much space that it was necessary for the operator to get up from her seat and walk to the desired switchboard location to insert the calling plug, often being required to reach way above her head for high positions. This greatly reduced the number of calls an operator could handle efficiently and thereby produced resultant delays and unsatisfactory service. The bulk of wires leading to the switchboard also occupied excessive valuable space and complicated the problem of installing the wiring and switchboard, as well as their maintenance.

15 Prior master stations have often required a switchboard area eight feet high and eight feet or more wide to serve 1000 rooms due to the bulk of wire terminals behind the board and the area of the equipment on the face of the board. A 20 cabinet embodying the master station for a 1000-room system arranged according to the present invention need be only 6 inches high and 10 inches wide. Where the dial system is used it may be even smaller.

25 It is thus possible, by providing a flexible cable carrying the conductors leading to the master station, to mount it on a portable stand or cart which can be placed at the location most convenient for the reach of the operator. Thus it 30 may be mounted beside an outside telephone switchboard so as to be readily accessible by the regular telephone operator. When desired it may be moved beside a desk for operation by a secretary during less busy periods.

35 It is also contemplated that the master station may be incorporated in a narrow switchboard of the same height as a conventional outgoing telephone switchboard so as to be placed beside the telephone switchboard and in effect, be made a part of it.

40 Moreover it is possible with the system to locate the master station at a remote point while achieving economy of wiring. The servicing of the system is also simplified by the present invention.

45 While the present invention, as to its objects and advantages, has been described herein as carried out in specific embodiments thereof, it is not desired to be limited thereby but it is intended to cover the invention broadly within the 50 spirit and scope of the appended claims.

What is claimed is:

1. A selective electric signaling system comprising in combination a plurality of groups of electric signaling devices, a source of electric current, 55 a first series of conductors, each conductor of which is individual to one of said groups, a second series of conductors, each of which is connected to at least one of said devices in each group, each of said signaling devices being connected between the member of the first series of conductors which is individual to its respective group and a member of said second series of conductors, switching devices for selectively connecting one terminal of said source to any one of said first series of conductors and for connecting the other terminal of said source to any one of said second series of conductors, a rectifier connected in series with each of said signaling devices, an electroresponsive device connected in series with each member of one of said series of conductors, a call-indicating signal device controlled by each of said electroresponsive devices, a second electro-responsive device connected to each member of said one series of conductors, 70 the call-indicating signal being controlled by each

11

said first-mentioned electroresponsive devices by the corresponding second electroresponsive device to return the signal to normal, and a plurality of energizing circuits for each of said second devices, each energizing circuit including a source of electric energy, manually-controlled contacts at an individual station and at one of said series of conductors.

2. A selective electric signaling system comprising a master station and a plurality of groups of room-call stations, an electric signaling device at each of said room-call stations, a rectifier in series with each of said signaling devices, a first series of conductors each connecting said master station with one terminal of the signaling devices at all of the room-call stations of one of said groups, a second series of conductors each connecting said master station with the other terminal of the signaling devices at one of said room-call stations in each of said groups, a source of electric energy, manually-controlled switching devices at said master station for connecting one terminal of said source to any selected member of said first series of conductors and for connecting the other terminal of said source to any selected member of said second series of conductors, a plurality of call-indicating signal devices located at said master station, and electroresponsive devices connected in series with each of one of said series of conductors, said call-indicating signal devices being respectively controlled by said electroresponsive devices to indicate the sending of a calling signal from said master station, a second series of electroresponsive devices, said second electroresponsive devices restoring said call-indicating signal devices respectively to non-indicating condition, a manual signaling switch at each of said room-call stations, a second source of electric energy, each of said manual signaling switches being connected between one terminal of said second source and a member of said one series of conductors, said second electroresponsive devices being connected respectively between members of said one series of conductors and the other terminal of said second source of energy, and a rectifier in series with each of said second devices.

3. A selective electric signaling system comprising a master station and a plurality of groups of room-call stations, an audible electric signaling device at each of said room stations, a rectifier in series with each of said signaling devices between the terminals of said room stations, a first series of conductors each connecting said master station with a first terminal of all of the room-call stations of one of said groups, a second series of conductors, each connecting said master station with a second terminal of one of said room stations in each of said groups, a source of alternating current energy, a switchboard plug having a contact connected to one terminal of said source, a plurality of switchboard jacks, each having a contact for cooperative engagement with said plug contact, said jack contacts being connected respectively to said first conductors, a plurality of push button switches each connected between the other terminal of said source and one of said second conductors, said system also comprising a series of relays each having a first winding for closing a pair of relay contacts and a second winding for opening said contacts, a series of switchboard lamps and energizing circuits therefor controlled respectively by said relay contacts, the first of said relay windings being connected respectively in

5 series with said first series of conductors, a rectifier in series with the sound of each of said windings, a second source of alternating current energy, each of said series combination of second windings and rectifier being connected between the first terminal of said second source and the conductor to which its associated first winding is connected, an answering switch at each of said room stations having a common contact being connected to said first terminal of said room station and said back contact being connected to the second terminal of said station through said audible signaling device, said front contact being connected to the second terminal of said second source of alternating current energy.

4. A selective electric signaling system comprising a master station and a plurality of groups of room-call stations, an audible electric signaling device at each of said room stations, a rectifier in series with each of said signaling devices between the terminals of said room stations, a first series of conductors each connecting said master station with a first terminal of all of the room-call stations of one of said groups, a second series of conductors, each connecting said master station with a second terminal of one of said room stations in each of said groups, a source of alternating current energy, a switchboard plug having a contact connected to one terminal of said source, a plurality of switchboard jacks, each having a contact for cooperative engagement with said plug contact, said jack contacts being connected respectively to said first conductors, a plurality of push button switches each connected between the other terminal of said source and one of said second conductors, said system also comprising a return-call check signal device at said master station and a second source of alternating current energy connected in series therewith, and a series of rectifiers, each of said rectifiers being connected between one of said jack contacts and one terminal of the series arrangement of said return-call signal and said second source of alternating current energy, an answering switch at each of said room stations having a common contact and a back and a front contact, said common contact being connected to said first terminal of said room stations and said back contact being connected to the second terminal of said station through said audible signaling device, said front contact being connected to the second terminal of said series arrangement of return-call signal and second source of alternating current energy.

5. A selective electric signaling system comprising a master station and a plurality of groups of room-call stations, an audible electric signaling device at each of said room stations and a rectifier in series with each of said signalling devices between the terminals of said room station, a first series of conductors, each connecting said master station with a first terminal of all of the room-call stations of one of said groups, a second series of conductors, each connecting said master station with a second terminal of one of said room stations in each of said groups, a source of alternating current energy, a stepping switch and a manual dial circuit for advancing the same, the stepping switch having a movable contact arm connected to one terminal of said source and a series of stationary contacts for cooperation therewith and connected respectively to said first conductors, a plurality of push button switches, each connected between the other terminal of said source and one of said second conductors, a series

of relays, each having a first winding for closing a pair of relay contacts and a second winding for opening said contacts, a series of indicating lamps and energizing circuits therefor controlled respectively by said relay contacts, the first of said relay windings being connected respectively in series with said first series of conductors, a rectifier in series with the second of each of said windings, a second source of alternating current energy, each of said series combination of second winding and rectifier being connected between a first terminal of said second source of alternating current energy and the conductors to which its associated first winding is connected, an answering switch at each of said room stations having a common contact and a back and front contact, said common contact being connected to said first terminal of said room station and said back contact being connected to the second terminal of said station through said audible signaling device, 10 15 20

said front contact being connected to the second terminal of said second source of alternating current energy.

EDWARD S. RUTH.
